TAPE RULE

Ragnar C. Nicholson, White Plains, and Nathan H. Schneider, New York, N. Y., assignors to Master Rule Manufacturing Co., Inc., New York, N. Y., a corporation of New York

Application December 24, 1943, Serial No. 515,514.

6 Claims. (Cl. 242—84.9)

1

This invention relates to improvements in tape rules, and especially in tape rules of the type employing a thin flexible graduated steel blade of curved cross-section.

The general object of this invention is to provide improvements in the features of construction of such rules which simplify the manufacturing and assembly operations and facilitate the repair and replacement of worn parts by the user.

The main feature of importance of this invention from which the other objects and advantages herein disclosed result, is in the supporting liner and brake shoe which forms a substantially frictionless support for the measuring blade as well as a guide in assembling the casing sections and a liner for the resulting housing which, in cooperation with a brake lever in off position, acts to support the measuring blade and which in brake on position locks the blade in extended position and insures against its "creeping."

Another object of the invention is to provide a neat structure of good appearance of such nature as to contribute to the ease and accuracy with which the device may be used.

An important object of the invention is to provide a construction of this type employing an improved form of braking arrangement for locating the tape in various extended positions.

Other and more detailed objects of the invention will be apparent from the following description of the preferred embodiment thereof.

This invention resides substantially in the combination, construction, arrangement and relative location of parts as will be described in detail below.

In the accompanying drawing,

Figure 1 is a side elevational view of a tape rule in accordance with this invention;

Figure 2 is an inside elevational view of the device looking towards the inner face of the side presented in Figure 1, as indicated by the line 2—2 of Figure 4, as it appears when the other half of the casing is removed;

Figure 3 is a cross-sectional view taken on the line 3—3 of Figure 1;

Figure 4 is a top plan view of the device;

Figure 5 is a cross-sectional view taken on the line 5—5 of Figure 2; and

2

Figure 6 is a cross-sectional view taken on the line 6—6 of Figure 2.

As is usual in tape rules of the type disclosed in the attached drawings, the flexible steel tape is stored in the form of a coil within a suitably shaped housing composed of two mating parts. Therefore, as illustrated in the drawings, the housing comprises the two cup-like sections 10 and 11 which are generally of the same configuration and construction, except as herein otherwise indicated. The two case sections are secured together by means of a screw 12 which passes through the section 11 to engage an internally threaded post P which is mounted on the other case section 10. Although the case section 10 has been removed in Figure 2, the post P is shown in this figure in association with the tape for illustrative purposes. The tape 13 is of thin flexible steel of normally curved cross-section suitably graduated and is wound into a coil within the casing, as illustrated. On its inner end there is attached, in accordance with usual practice, a coil spring whose end in turn is anchored to the post P so that as the tape is extended the spring is tensioned to aid in returning the graduated tape back into the housing. This spring as is usual is not sufficiently strong to pull the tape back into the housing, but does aid in its return thereto upon the application of a light pushing force on the projecting end of the tape.

The side walls of the case sections 10 and 11 each have flange sections of unequal width. This is particularly clear from Figure 4, wherein the wider flange sections 16 and 17 abut to close the housing, while the narrower flange sections 14 and 15 provide an opening through which the adjacent portion of the tape 13 is visible, as is clear from Figure 4, while the edges thereof are guided by the shallow flanges 14 and 15. The housing, as is clear from Figures 1 and 2, is of generally rectangular cross-sectional shape, although it has flatly curved corners on one diagonal, a sharply curved corner at one end of the other, and a right angle corner at the other end of the latter diagonal. The tape 13 passes from the coil to one flatly curved corner, as shown in Figure 2, runs along the top side of the casing 50 at which the flanges 14 and 15 lie, and issues

from an opening in the casing at the right angle corner, all as is quite clear from Figure 2.

Mounted within the casing on the section 11 is a support and brake shoe arm 18 having a right angle extension 19 by means of which it is attached as by spot welding, to the housing section 11 by the wider flange 17 thereof, as clearly shown in Figure 5. The result is the formation of a seating and guide shoulder 20 by means of which the flange 16 of the other corner section 10 is accurately positioned. The arm 18 is supported so to speak, as a cantilever extending into the housing under the tape 13 to form a support for it, as illustrated in Figure 2. The inner free end of the arm 18 is curved so as to have a substantially complementary shape to the adjacent portion of the housing, as illustrated at 21.

Pivotedly mounted on a pivot pin 22, secured in the casing section 11, is a thumb lever 23 which has a right angle extension 24 (see particularly Figure 3), which extends through an arcuate slot 25 in the casing, so as to project under the curved end 21 of the lever 18. The center of the pivot pin 22 is so mounted and the parts are so proportioned that when the thumb lever 23 is rotated in a counterclockwise direction, Figure 2 (clockwise Figure 3), the cam 24 presses the curved end 21 of the arm 18 outwardly against the lower face of the tape 13 so as to press it firmly against the inner face of the adjacent flange portions of the housing. It is important to note, as is illustrated in Figure 3, that when the cam 24 is at the lower end of the slot 25 and can go no further, the curved end 21 of the arm 18 rests on it forming a support at the time the brake is released so that if any undue pressure is applied to the arm 18 it cannot be permanently bent or distorted.

The flange portion 17 of the casing section 10 is also provided with another guide and seating plate 26 which is spot welded on the inner surface of the flange 17 so as to form a seat for the flange 16 of the casing section 10 and an indexing or positioning shoulder 27, all as illustrated in Figure 6. Thus in assembling the two housing sections the section 10 fits over the plates 19 and 26 so as to guide the two parts together in accurate relation and greatly aid in their assembly.

It will be seen that the graduated tape 13 is guided on the inside of the housing and supported at its under surface by the supporting arm 18 and guided at its upper surface by means of the shallow flanges 14 and 15. The flanges 14 and 15 are continuous as distinguished from some prior art devices, thereby facilitating assembly, minimizing wear on the graduated edges of the tape, and improving the finished appearance of the device. The supporting arm 18, it will be noted, acts as a liner for a substantial portion of the housing when its sections are in assembled relation as well as a guide in facilitating the final assembly of the parts. It also acts as a support for the measuring blade both in locked and in unlocked position of the locking device. In unlocked position of the locking device the lock cam is engaged by this supporting liner to prevent its inward displacement against undue pressure thus insuring against damage of the structure in use. With the brake in unlocked position this liner acts as a nearly frictionless support for the measuring blade as it is moved out of and into the casing.

A valuable commercial feature of the structure herein disclosed is found in the fact that the interior construction of the device does not re-

quire any modifications of the outer appearance of the housing by way of unsightly tell tale rivets and other fastening devices. The construction is such that the two housing sections can only be assembled in the proper relation, and as they are assembled the parts are guided and brought to the proper seating position without difficulty.

As illustrated in Figure 1, when the outside measurements of an object are to be taken they are taken between the straight face A and the hooked end of the tape 13. The reading, of course, is taken at the point where the tape issues from the ends of the flanges 14 and 15. When an inside measurement is to be taken it is taken between the opposite straight side B and the outer face of the hooked end of the tape. In this case the reading is taken at the arrow C, Figure 1, which is at the point where the tape first enters the enlarged opening between the flanges 14 and 15, as will be seen from an examination of Figure 3.

From the above description of a preferred embodiment of this invention it will be apparent to those skilled in the art that the subject matter comprising the novel features thereof may be embodied in other physical forms, and we do not therefore desire to be strictly limited to the disclosure given herein but rather by the scope of the claims granted us.

What is claimed is:

1. A housing for a tape rule comprising a pair of similarly shaped flanged sections each having a flat side, the flanges of said sections extending around the periphery thereof but respectively having relatively narrow portions at the flat sides to form an opening in the casing through which the tape issues tangentially at the end thereof, and at which it is exposed, guide plates secured to the flange of one section on the inner face thereof and projecting beyond the flange edge to form a guide seat for the flanges of the other section, one of said guide plates underlying the tape at said opening to form a guide for said tape, and means for securing said sections together.
2. A tape rule of the type described comprising a housing having a graduated tape coiled therein and issuing from an opening in the housing, a cantilever arm attached to the casing adjacent said opening and extending parallel to the wall along which the tape extends to said opening, said tape lying between the casing wall and arm so that the arm forms a support therefor, and a brake member mounted on said casing and engaging the free end of said cantilever arm for gripping the tape between the arm and the housing for a substantial portion of the tape length.
3. In the combination of claim 2, said casing comprising a pair of complementary flanged parts and the supporting end of said arm forming a guide for said parts to hold the flanges in abutting relation.
4. A tape rule of the type described comprising a housing composed of two complementary flanged parts forming a closed housing when assembled with the flanges abutting and having a tape exit opening, a graduated tape coiled in said housing and projecting through said opening, a cantilever arm lying on the under side of said tape and secured at one end to the flange of one of said housing parts at said opening, the other end of said arm being free and said tape extending from the coil through the passage formed between the arm and the adjacent portion of the housing for a substantial distance, and a brake pivotally mounted on the housing and

2,446,020

5

engaging the free end of said arm to grip the tape between the housing and said lever.

5. In the combination of claim 4, said tape coil being attached to the other housing part.

6. A tape rule according to claim 4, characterized in that said cantilever arm projects beyond said housing flange to which it is attached and forms a guide and seat for the other housing part.
